CLAIM

The ornamental design for a shoe upper, as shown and described.

DESCRIPTION

FIG. 1 is a front perspective view of my shoe upper, according to a first embodiment of the design;

FIG. 2 is a front view thereof;

FIG. 3 is a right-side view thereof;

FIG. 4 is a left-side view thereof;

FIG. 5 is a top view thereof;

FIG. 6 is a front perspective view of my shoe upper, according to a second embodiment of the design;

FIG. 7 is a front view thereof;

FIG. 8 is a right-side view thereof;

FIG. 9 is a left-side view thereof;

FIG. 10 is a top view thereof;

FIG. 11 is a front perspective view of my shoe upper, according to a third embodiment of the design;

FIG. 12 is a front view thereof;

FIG. 13 is a right-side view thereof;

FIG. 14 is a left-side view thereof;

FIG. 15 is a top view thereof;

FIG. 16 is a front perspective view of my shoe upper, according to a fourth embodiment of the design;

FIG. 17 is a front view thereof;

FIG. 18 is a right-side view thereof;

FIG. 19 is a left-side view thereof;

FIG. 20 is a top view thereof;

FIG. 21 is a front perspective view of my shoe upper, according to a fifth embodiment of the design;

FIG. 22 is a front view thereof;

FIG. 23 is a right-side view thereof;

FIG. 24 is a left-side view thereof; and,

FIG. 25 is a top view thereof.

The broken lines shown in the drawings represent portions of the shoe upper article that form no part of the claimed design.
